(57) **CLAIM**

The ornamental design for a brassiere underwire retainer, as shown and described.

DESCRIPTION

FIG. 1 is a perspective view of a brassiere underwire retainer;

FIG. 2 is a front elevation view thereof;

FIG. 3 is a rear elevation view thereof;

FIG. 4 is a left elevation side view thereof, wherein a right side elevation view is a mirror image of the left side elevation view;

FIG. 5 is a top plan view thereof;

FIG. 6 is a bottom plan view thereof;

FIG. 7 is a cross sectional left side elevation view thereof, wherein a cross sectional right-hand side view is a mirror image of the cross sectional left-hand side view; and,

FIG. 8 is an enlarged detail view of the upper clip portion of the design as shown in FIGS. 1-7, and is shown separately for clarity of illustration.

1 Claim, 7 Drawing Sheets
